JEWELRY CLASP

Michael Pagliuca, New York, N. Y., assignor to Alcore Novelty Company, New York, N. Y.

Application August 17, 1950, Serial No. 11,808

Term of patent 14 years
(Cl. D45—4)

To all whom it may concern:

Be it known that I, Michael Pagliuca, a citizen of the United States, residing at 2309 Second Avenue, New York, in the county of New York and State of New York, have invented a new, original, and ornamental Design for a Jewelry Clasp, of which the following is a specification, reference being had to the accompanying drawing, constituting a part hereof.

Fig. 1 is a perspective view of a jewelry clasp embodying my new design, illustrating the clasp in an open position;

Figs. 2 and 3 are top plan and side elevational view, respectively, of the clasp; and

Fig. 4 is a side elevational view of the bottom portion only of the clasp.

I claim:

The ornamental design for a jewelry clasp, substantially as shown.

MICHAEL PAGLIUCA.
